UNITED STATES PATENT OFFICE.

HENRY A. WEIHMANN, OF PHILADELPHIA, PENNSYLVANIA, ASSIGNOR TO
SIMONS, BROTHER & CO., OF SAME PLACE.

DESIGN FOR A CANE OR UMBRELLA HANDLE.

SPECIFICATION forming part of Design No. 19,969, dated July 1, 1890.

Application filed April 15, 1890. Serial No. 348,087. Term of patent 3½ years.

To all whom it may concern:

Be it known that I, HENRY A. WEIHMANN, a citizen of the United States, residing in Philadelphia, in the county of Philadelphia and State of Pennsylvania, have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

A is the body part, and extends upwardly in a sinuous curve and terminates in a large

15 crook B, and a rear extension or heel C. The lower portion of the body is formed by the spiral ornamentation D and the upward and spreading ribs E, which are bounded on the bottom by the double annular band F of plain

20 surface. The upper portion of the body and the crook B are wrapped with ribbed work G,

substantially as shown, part of which runs into the heel-extension C. This ribbed work is brought over the end of the crook B to impart an ornamentation, as at H.

25

The general surface of the handle is plain, and the parts adjacent to the ribbed and ornamental work are relieved by shaded work.

The handle is made of any suitable material.

30

Having now described my new design, what I claim as new, and desire to secure by Letters Patent, is—

The design for cane or umbrella handles, substantially as herein described and shown. 35

In testimony of which invention I have hereunto set my hand.

HENRY A. WEIHMANN.
